UNITED STATES PATENT OFFICE

FRANK W. SEVERIN, OF CHICAGO, ILLINOIS

LINE CASTING MACHINE

Application filed December 31, 1931. Serial No. 584,135.

The invention relates generally to machines for casting lines of type for printing purposes. More particularly the invention relates to that type of line casting machine which is driven by an electric motor and embodies (1) a horizontally extending shaft which is known as an intermediate shaft and is disposed at one side of the main frame of the machine and serves to drive the key-board mechanism and the assembling and distributing mechanisms for the matrices; (2) a clutch which is located at the back of the machine and comprises a loosely mounted, motor-driven wheel and radially movable clutch shoes which are disposed within the wheel and are adapted, when shifted into engagement with the inner periphery of the wheel, to drive a countershaft from the wheel; and (3) a cam shaft which is disposed at the other side of the main frame of the machine, is driven from the countershaft by a pinion and gear connection and operates, when driven, to drive the slug-ejecting mechanism, the pot cam, the pump cam, the first and second justification cams, the mold-turning cam, the first elevator cam, the distributor-shifting cam, the elevator transfer and line delivery cam and other operating parts of the machine.

Heretofore, it has been customary in connection with a line casting machine of this type, to provide the rotor shaft of the electric motor with a pinion and to drive the clutch wheel by a gear which is secured to one side of the wheel and meshes with the pinion. It has also been customary to drive the intermediate shaft from the clutch wheel by means of a flat endless belt which extends around the clutch wheel and a pulley on the intermediate shaft. In practice it has been found that in a drive of this character, the pinion on the motor and the gear on the clutch wheel wear rapidly and transpositions in type setting and faulty distribution of the matrices often occur. The wear of the pinion and gear is due to possible misalignment of the gear teeth and to the pinion and gear running out of true pitch line. It is also due to the fact that the pinion is extremely small in order that there is the necessary speed reduction between

the motor and the clutch. The transpositions in type setting and the faulty distribution of the matrices are attributable to the fact that the belt between the clutch wheel and the intermediate shaft slips after it stretches and becomes worn.

One object of the present invention is to provide a line casting machine which is an improvement upon previously designed machines of the same general type by virtue of the fact that it comprehends a novel drive between the electric motor and the intermediate and cam shafts whereby the usual pinion and gear connection between the rotor of the motor and the clutch wheel is eliminated and slippage in the drive of the intermediate shaft is avoided. In general this drive comprises an endless belt between a motor-driven pulley and the clutch wheel and a second endless belt between another motor-driven pulley and a pulley on the intermediate shaft. An advantage of utilizing an endless belt between the motor and the clutch wheel in lieu of a pinion and gear connection is that the machine runs quietly and the wear factor is reduced to a minimum. In addition, there is sufficient flexibility to take up the shock which results when the clutch shoes are shifted into engagement with the inner periphery of the wheel in order to effect a driving connection between the cam shaft and the clutch. An advantage of utilizing an endless belt between the motor and the intermediate shaft is that the load is distributed and the belt construction may be such that slippage in the drive of the intermediate shaft may be avoided.

Another object of the invention is to provide a line casting machine of the character under consideration in which the electric motor for driving the intermediate and cam shafts is of the "geared head" type and the two pulleys for driving the clutch wheel and intermediate shaft from the motor are mounted on a shaft which is driven by the geared head of the motor.

A further object of the invention is to provide a line casting machine of the type to which the invention relates, in which the electric motor for driving the cam and inter-

mediate shafts is positioned above the clutch and is supported so that it may be moved vertically so as to tighten the belt for the clutch wheel and may be moved horizontally so as to tighten the belt for the intermediate shaft.

A still further object of the invention is to provide a line casting machine in which the driving mechanism thereof permits of ready installation, repair and adjustment and is exceedingly efficient in operation.

Other objects of the invention and the various advantages and characteristics of the present construction will be apparent from a consideration of the following detailed description to those who are skilled in the art.

The invention consists in the several novel features which are hereinafter set forth and are more particularly defined by the claims at the conclusion hereof.

In the drawings which accompany and form a part of this specification or disclosure and in which like numerals of reference denote corresponding parts throughout the several views:

Figure 1 is a perspective of a line casting machine embodying the invention;

Figure 2 is a side view, illustrating in detail the manner in which the motor is supported so that it may be shifted horizontally so as to tighten the belt between the motor and the intermediate shaft;

Figure 3 is a rear view, illustrating the construction of the bracket which supports the electric motor and exhibiting the manner in which the bracket may be adjusted vertically so as to effect vertical shift of the motor when it is desired to tighten the belt between the motor and the clutch wheel; and

Figure 4 is a transverse section on the line 4—4 of Figure 3.

The machine which forms the subject matter of the present invention is designed to cast lines of type for printing purposes and comprises a main frame 5, a keyboard 6, magazines 7 and distributing mechanism 8. The main frame 5 is formed of cast metal and embodies a side piece 9. The magazines 7 are supported on the central portion of the frame 5 and contain the matrices which are used in connection with the casting operation of the machine to form lines of type and are fed to assembling mechanism (not shown). Feed of the matrices to the assembling mechanism is effected by the keyboard 6 and escapement mechanism which is operated by manipulation of the keys of the keyboard. In addition to the keyboard 6, the magazines 7 and the distributing mechanism 8, the machine comprises first elevator mechanism for successively shifting complete lines of matrices into a casting position, mechanism for locking together the matrices and space bands between the matrices, mechanism for shifting the space bands in order to effect

justification or line spacing, a rotary mold disk, a pump for forcing molten metal from a pot against the matrices for slug-forming purposes, mechanism for ejecting the slugs from the mold disk and second elevator mechanism for carrying the matrices after the casting operation to the distributing mechanism 8. These parts are of standard construction and with the exception of the lever of the second elevating mechanism, are not shown in the drawings. The distributing mechanism 8 receives the matrices from the second elevator mechanism and distributes them in their proper positions in the magazines 7.

The keyboard 6 and the assembling and distributing mechanisms are driven from a horizontally extending shaft 10 which is commonly known as the intermediate shaft of the machine. This shaft is located at one side of the main frame 5 of the machine and is journaled in a bearing 11. The keyboard 6 is driven from the shaft 10 by means of an endless belt 12. The latter extends around a pulley 13 on the shaft 10 and a pulley 14 on the drive shaft of the keyboard. The distributing mechanism 8 is driven from the shaft 10 by an endless belt 15. This belt extends around a pulley 16 on the extreme outer end of the shaft 10 and a pulley 17 on the drive shaft of the distributing mechanism.

The first elevator mechanism, the mechanism for locking the matrices and the space bands, the pump, the mechanism for effecting justification of the matrices, the second elevator mechanism and other operating parts of the machine are driven by means of a series of cams on a horizontally extending shaft 18. The latter is disposed at the back of the machine and has one end thereof journaled in a bearing 19 on the top of the side piece 9 of the main frame 5. Drive of the shaft 18 which is generally termed the cam shaft of the machine, is effected through the medium of a clutch 20. This clutch is located adjacent to the end of the shaft 18 which is journaled in the bearing 19 and comprises a wheel 21 and a pair of radially movable shoes 22. The wheel 21 is loosely mounted on one end of a countershaft 23 and is located in close proximity to the side piece 9 of the main frame of the machine. The countershaft 23 is journaled in the side piece 9 and is connected to the cam shaft 18 by a gear 23^a and a pinion 18^a. The clutch shoes 22 are mounted on an arm 24 and are shiftable into and out of engagement with the inner periphery of the wheel 20 by links 25. The arm 24 extends diametrically across the space within the clutch wheel 20 and is keyed or otherwise fixedly secured to the countershaft 23. The links 25 are suitably controlled from the front of the machine and are adapted, when moved in one direction, to

shift the shoes 22 into engagement with the inner periphery of the clutch wheel so that the wheel is connected to drive the counter-shaft 23 and the cam shaft 18 through the 5 medium of the arm 24.

The intermediate shaft 10 and the clutch 20 are driven by means of an electric motor 26. This motor is of the "geared head" type and is supported on a cast metal bracket 27 10 directly above the clutch 20. The bracket 27 embodies a pair of eyes 28 at the ends thereof and has its top portion shaped so as to form a flat, horizontally extending platform 29 for the motor 26. The motor 26 15 comprises an armature 30 and a casing 31. The latter embodies a gear compartment 32 at one end thereof and has feet 33 which rest upon the platform 29 of the bracket 27. The rotor shaft of the armature 30 extends into 20 the gear compartment 32 and is provided with a pinion 34. This pinion meshes with a gear 35 which is disposed in the gear compartment 32 and is keyed or otherwise secured to one end of a stub shaft 36. The latter 25 extends through and is journaled in a closure cap 37 for the compartment 32 and is driven through the medium of the pinion 34 and the gear 35 when current is supplied to the motor. Drive of the clutch 20 from 30 the motor 26 is effected by means of an endless V-belt 38. The latter extends around a grooved pulley 39 on the stub shaft 36 and a grooved pulley 40 at one side of the clutch 35 wheel 21. The pulley 40 is secured in any suitable manner to the clutch wheel 21 and operates when driven by the motor 26 to rotate the clutch wheel. By employing the V-belt 38, a drive is effected between the motor and the clutch which is exceedingly efficient in operation and is an improvement 40 upon a pinion and gear connection in that it is silent and less likely to wear. An advantage and characteristic of a V-belt drive between the motor and clutch over a pinion and gear connection is that there is sufficient flexibility to take up the shock which results when the clutch shoes are shifted into engagement with the inner periphery of the clutch wheel.

50 Drive of the intermediate shaft 10 from the motor 26 is effected by means of an endless V-belt 41. This belt extends around a grooved pulley 43 on the stub shaft 36 and a grooved pulley 42 on the intermediate shaft. 55 The grooved pulley 43 is keyed or otherwise fixedly secured to the stub shaft 36 and is positioned outwardly of the pulley 39. By utilizing the V-belt 41 as the driving medium for the intermediate shaft 10 instead of connecting the shaft 10 to be driven by the clutch wheel 21 as has been done heretofore, there is little likelihood of slippage and no load is placed upon the clutch 20 by the mechanisms and parts which are driven by the shaft 60 10.

The bracket 27 for supporting the motor 26 is connected to the bearing 19 at the top of the side piece 9 of the main frame of the machine by means of a pair of vertically extending tubular bolts 44. These bolts extend 70 through the eyes 28 and are connected to the latter by screw thread connections 45. They rest upon the bearing 19 and are adapted when rotated, to raise and lower the bracket 27 and the motor 26. When it is desired to 75 tighten the endless V-belt 38 between the motor and the wheel 21 of the clutch, the motor 26 is raised. This is accomplished by rotating or turning the bolts 44 so as to raise the bracket 27. When it is desired to loosen 80 the belt 38, the bolts 44 are rotated in the opposite direction so as to lower the bracket 27 and the motor 26. The bolts 44 are provided at the lower ends thereof with polygonal heads 46 so that they may be turned by 85 a wrench or similar turning tool. Lateral displacement of the bolts is prevented by means of a pair of vertically extending posts 47. The latter extend through the bolts and have the lower ends thereof secured to the bearing 19 for the cam shaft 18. The upper ends of the posts 47 are threaded and embody nuts 48. These nuts abut against the upper ends of the eyes 28 and operate, when tightened, to lock the bracket 27 to the bolts 44. 90 The bracket 27 and the bolts 44 exemplify simple means for supporting the motor 26 so that it may be raised in order to tighten the endless V-belt 38.

In order to tighten the endless V-belt 41 100 between the motor and the intermediate shaft 10, the motor is shifted horizontally on the platform 29 at the top part of the bracket 27. For the purpose of facilitating shift of the motor and holding the motor in place, a pair of guide pieces 49 are provided. These guide pieces are supported from the legs 33 of the motor casing 31 by bolts 50 and fit against the side edges of the platform 29 so as to form a 105 connection between the motor and the bracket 27 whereby the motor may be slid horizontally and rearwardly in order to take up the slack in the belt 41. The inner side parts of the guide pieces 49 embody flanges 51 which fit 110 under the side margins of the platform 29 and serve to clamp the motor in place when the bolts 50 are tightened. When it is desired to shift the motor 26 for belt-tightening purposes, the bolts 50 are loosened and the motor is slid rearwardly. After tightening 115 the belt 41, the bolts 50 are tightened so as to clamp the flanges 51 against the side margins of the platform 29 and thus secure the motor 26 in place. The platform 29 and the guide pieces 49 on the feet of the motor casing 120 exemplify simple means for supporting the motor so that it may be shifted horizontally in order to tighten the belt 41. By virtue of the fact that the motor 26 is located directly 125 above the clutch 20, the motor may be shifted

horizontally to tighten the belt 41 without materially affecting the belt 38.

The herein described line casting machine drive may be manufactured at a low and reasonable cost and is extremely efficient in operation. This is primarily attributable to the fact that the driving mechanism between the motor and the intermediate and cam shafts is of novel design and permits of ready installation, repair and adjustment.

The invention is not to be restricted to the details set forth, since these may be modified within the scope of the appended claims, without departing from the spirit and scope 15 of the invention.

Having thus described the invention, what I claim as new and desire to secure by Letters Patent, is:

1. The combination with a line casting machine embodying an intermediate shaft at 20 one side of the main frame thereof connected to drive the keyboard and the assembling and distributing mechanisms, a clutch at the back of the machine comprising a drive-element and a driven element, and a shaft at the 25 other side of the frame connected to be driven by the drive-element of the clutch and operative to drive cams for actuating other operating parts of the machine, of a motor, a 30 drive connection between the motor and the cam shaft consisting of a pulley driven by the motor, a pulley connected to the drive-element of the clutch and an endless belt extending around the two pulleys, and driving 35 means for the intermediate shaft comprising a pulley on said shaft and an endless belt extending around the last mentioned pulley and connected to be driven by the motor.

2. The combination with a line casting machine embodying an intermediate shaft at 40 one side of the main frame thereof connected to drive the keyboard and the assembling and distributing mechanisms, a clutch at the back of the machine comprising a drive-element and a driven element, and a shaft at the 45 other side of the frame connected to be driven by the driven element of the clutch and operative to drive cams for actuating other operating parts of the machine, of an 50 electric motor, a drive connection between the motor and the cam shaft consisting of a pulley connected to and driven by the motor, a pulley connected to the drive-element of the clutch and an endless belt extending around 55 the two pulleys, and a drive connection between the motor and the intermediate shaft consisting of a pulley connected to and driven by the motor, a pulley on the intermediate shaft and an endless belt extending around the two last mentioned pulleys.

3. The combination with a line casting machine embodying an intermediate shaft at 60 one side of the main frame thereof connected to drive the keyboard and the assembling and distributing mechanisms, a clutch at the 65

back of the machine comprising a drive-element and a driven element, and a shaft at the other side of the frame connected to be driven by the drive-element of the clutch and operative to drive cams for actuating other operating parts of the machine, of an electric motor, a drive connection between the motor and the cam shaft consisting of a grooved pulley connected to and driven by the motor, a grooved pulley connected to the 70 drive-element of the clutch and an endless V-belt extending around the two pulleys, and a drive connection between the motor and the intermediate shaft consisting of a pulley associated and driven with the first mentioned pulley of the drive connection for the cam shaft, a grooved pulley on the intermediate shaft and an endless V-belt extending around the two pulleys of the drive connection 75 for the intermediate shaft.

4. The combination with a line casting machine embodying an intermediate shaft at one side of the main frame thereof connected to drive the keyboard and the assembling and distributing mechanisms, a clutch at the back 90 of the machine comprising a drive-element and a driven element, and a shaft at the other side of the frame connected to be driven by the drive-element of the clutch and operative to drive cams for actuating other operating 95 parts of the machine, of an electric motor of the "geared head" type, a drive connection between the motor and the cam shaft consisting of a pulley fixed to the gear-driven shaft of the motor, a pulley connected to the drive-element of the clutch and an endless belt extending around the two pulleys, and driving 100 means for the intermediate shaft comprising a pulley on said shaft and an endless belt extending around the last mentioned pulley and connected to be driven by the motor.

5. The combination with a line casting machine embodying an intermediate shaft at one side of the main frame thereof connected to drive the keyboard and the assembling and distributing mechanisms, a clutch at the back of the machine comprising a drive-element and a driven element, and a shaft at the other side of the frame connected to be driven by the drive-element of the clutch and operative 110 to drive cams for actuating other operating parts of the machine, of an electric motor of the "geared head" type, a drive connection between the motor and the cam shaft consisting of a pulley fixed to the gear-driven shaft of the motor, a pulley connected to the drive-element of the clutch and an endless belt extending around the two pulleys, and a drive connection between the motor and the intermediate shaft consisting of a pulley 115 on the aforesaid geared shaft of the motor, a pulley on the intermediate shaft and an endless belt extending around the two last mentioned pulleys.

6. The combination with a line casting ma- 120

chine embodying an intermediate shaft at one side of the main frame thereof connected to drive the keyboard and the assembling and distributing mechanisms, a clutch at the back 5 of the machine comprising a drive-element and a driven element, and a shaft at the other side of the frame connected to be driven by the drive-element of the clutch and operative to drive cams for actuating other operating 10 parts of the machine, of an electric motor, a belt and pulley connection between the motor and the drive-element of the clutch, a belt and pulley connection between the motor and the intermediate shaft, and means for supporting 15 the motor so that it may be moved bodily in order to tighten the belts of the two connections.

7. The combination with a line casting machine embodying an intermediate shaft at 20 one side of the main frame thereof connected to drive the keyboard and the assembling and distributing mechanisms, a clutch at the back of the machine comprising a drive-element and a driven element, and a shaft at the other 25 side of the frame connected to be driven by the drive-element of the clutch and operative to drive cams for actuating other operating parts of the machine, of an electric motor positioned above the clutch, a belt and pulley connection between the motor and the drive-element of the clutch, a belt and pulley connection between the motor and the intermediate shaft, and means for supporting 30 the motor so that it may be shifted vertically to tighten the belt of the first mentioned connection and so that it may be shifted laterally in order to tighten the belt of 35 the second mentioned connection.

8. The combination with a line casting machine 40 embodying an intermediate shaft at one side of the main frame thereof connected to drive the keyboard and the assembling and distributing mechanisms, a clutch at the back of the machine comprising a drive-element and a driven element, and a shaft at the other side of the frame connected to be driven by the drive-element of the clutch and operative to drive cams for actuating other operating parts of the machine, of an electric 45 motor positioned above the clutch, a belt and pulley connection between the motor and the drive-element of the clutch, a belt and pulley connection between the motor and the intermediate shaft, a bracket for supporting the 50 motor connected to the frame of the machine so that it may be shifted vertically in order to raise the motor when it is desired to tighten the belt of the first mentioned connection, and a sliding connection between the motor 55 and the bracket whereby the motor may be shifted laterally when it is desired to tighten the belt of the second mentioned connection.

Signed at Chicago, Illinois, this 19th day of November, 1931.
